Primary Examiner — Mary Ann Calabrese*Assistant Examiner* — Catherine Ho(74) *Attorney, Agent, or Firm* — Reinhart Boerner Van Deuren P.C.(57) **CLAIM**

I claim the ornamental design for a mobile information desk, as shown and described.

DESCRIPTION

FIG. 1 is a side view of a mobile information desk, showing my new design;

FIG. 2 is an opposite side view thereof;

FIG. 3 is a bottom view thereof;

FIG. 4 is a top view thereof;

FIG. 5 is a front view thereof;

FIG. 6 is back view thereof; and,

FIG. 7 is a perspective view thereof.

The broken line portion of the figure drawings is included to show portions of the article the form no part of the claimed design.
